X-RAY APPARATUS

Zed J. Atlee, Elmhurst, and James C. Filmer, Wheaton, Ill., assignors to General Electric X-Ray Corporation, Chicago, Ill., a corporation of New York

Application October 22, 1942, Serial No. 462,954

14 Claims. (Cl. 250—90)

The present invention relates in general to electrical insulation and has more particular reference to means for and method of insulating X-ray generators in shockproof manner, the invention relating to the use of an evaporable liquid medium in the shockproof housing of an X-ray generator or tube for insulating purposes, including novel features of tube housing design for the accommodation and utilization of the evaporable medium in gaseous condition for insulating purposes.

An important object of the invention resides in using, as an insulating medium for electrical equipment, a medium which normally exists in its liquid phase at low temperature or when under compression, but which vaporizes at a relatively low temperature at atmospheric pressure; a further object being to employ a chlorine-fluorine derivative of aliphatic hydrocarbons for insulating electrical apparatus, especially X-ray generators.

Another important object is to utilize a chlorine-fluorine derivative of methane or ethane, which have a substantially gaseous phase within the range of temperature normally encountered within the range of electrical devices; a further object being to employ dichloro-difluoromethane, CCl_2F_2 , or dichloro-tetrafluoroethane, $C_2Cl_2F_4$, preferably the latter, as an insulating medium.

Another important object is to provide an improved shockproof mounting for an X-ray generator comprising a casing in which the generator may be supported, and means for charging the insulating medium in the casing after the same has been closed and sealed upon the generator.

Another important object is to provide a substantially sound and shockproof casing for an X-ray generator, more particularly a generator of the rotating anode type, the operation of which develops a certain amount of undesirable noise and vibration; a further object being to eliminate noise and vibration by supporting the vibrator in its shockproof housing by means of resilient supports embodying tube mounting elements of rubber-like material, while insulating the generator by a gaseous atmosphere comprising an evaporable medium capable of maintaining a desired pressure within the housing by evaporation therein from the liquid phase at the operating temperature of the generator; a further object being to utilize an insulating medium in the presence of which the rubber-like mounting elements do not appreciably deteriorate.

Another important object is to employ an insulating medium for the purposes mentioned, the

medium being progressively evaporable with increase in temperature to produce a corresponding increase in pressure within the generator housing, the medium having the further characteristic of increasing its dielectric strength in proportion to increase in pressure.

Another important object is to provide an improved shockproof X-ray generator housing of minimum weight and compactness, which through the employment of an evaporable insulating medium therein is characterized by the absence of reservoir and other attachments heretofore necessary in apparatus of the character mentioned for maintaining a supply of liquid insulating medium in the housing.

Among the other numerous important advantages of the invention is to simplify and reduce the over-all weight of an X-ray generator and its enclosing housing by employing a gaseous insulating medium in place of the liquid oil heretofore used, and incidentally to facilitate the operation and servicing of X-ray apparatus, since the weight, in liquid condition, of the evaporable medium employed for insulating any selected generator in accordance with the teachings of the present invention, is approximately two per cent of the weight of oil required for insulating a generator of like size in accordance with previous insulating technique.

These and numerous other important objects, advantages, and inherent functions of the invention will be fully understood from the following description, which, taken in connection with the accompanying drawing, discloses a preferred embodiment of the invention.

Referring to the drawing:

Figure 1 is a perspective view of a generator housing embodying the present invention;

Figure 2 is a sectional view taken substantially along the line 2—2 in Figure 1, showing the X-ray generator in mounted position within the housing;

Figure 3 is an enlarged sectional view taken through the generator mounting shown in the right-hand end of the generator, as illustrated in Figure 2;

Figure 4 is an enlarged sectional view taken through the generator mounting shown at the left-hand end of the generator, as illustrated in Figure 2;

Figure 5 is an enlarged sectional view taken substantially along the line 5—5 in Figure 2; and

Figure 6 is a sectional view showing a housing attachment comprising a reservoir.

To illustrate the invention the drawing shows

a housing 11 for an X-ray generator 13, which, in the illustrated embodiment, comprises a rotating anode 15 and an opposing cathode 17 mounted within a sealed envelope 19, the anode being supported for rotation on suitable bearings within the envelope and having a stem 21 extending outwardly of the envelope at one end thereof for electrically connecting the anode in the generator operating circuit outwardly of the envelope. The cathode 17 is supported on the envelope at the other end thereof and comprises an electron emitting filament in position to project electrons on the facing target surface 23 of the anode when the filament is electrically energized, electrical power for energizing the filament being delivered thereto by filament conductors 25 extending outwardly of the envelope through suitable conductor seals.

The X-ray generator 13 may comprise a generator of the sort illustrated and described in 20 the co-pending application of Zed J. Atlee for United States Letters Patent for X-ray tube, Serial No. 390,322, filed April 25, 1941, upon which Letters Patent No. 2,311,725 issued February 23, 1943, in which the anode 15 is caused to rotate within the envelope by motor means 27 disposed outwardly of the envelope portions 19 enclosing the anode, the motor being mounted on a suitable bracket 28 in the casing in position to receive the anode end of the generator. The cathode 17 carries a stem 29 extending axially outwardly of the envelope at the cathode carrying end thereof, said stem being preferably fitted with an insulated terminal block 31 to which the filament conductors 25 are connected.

The housing 11 is generally cylindrical and provides a generally cylindrical cavity 30 for receiving the generator 13. The housing 11 is provided with an opening 33 and the housing is provided with an annular rim or collar 35 forming an outwardly extending hood at said opening. The opening 33 is covered and closed by means of a plate of preferably cup-shaped configuration and having a marginal flange 39 sealingly secured, as by screws 41, on an annular seat 42 formed in 45 the hood 35.

The housing 11, preferably at its side opposite from the opening 35, is formed with a pair of spaced apart chambers 43, 44, the walls of which are formed integral with the walls of the housing. These chambers 43, 44 are each closed at one end, as shown at 45, and are open at the other end to receive cable terminals 47, 48, which may be inserted axially within the chambers 43, 44 whereby to electrically connect cables 49, 50 with terminal blocks 51 and 52, respectively, supported within the closed ends of the chambers 43, 44 on terminal receiving sleeves 53, 54, of tapered cylindrical configuration, which receive the cable terminals 47, 48 within the chambers 43, 44. These receptacles are flanged, as at 55, at the open ends thereof for sealing connection with corresponding annular flanges at the open ends of the chambers 43, 44. The inner, or closed, ends of the receptacles are fitted with the terminal members 51, 52 through which the conductors of the cables 49, 50 may be electrically connected with conductors within the housing 11 when the terminal members 47, 48 are inserted in said receptacles 53, 54.

At each of its opposed ends the generally cylindrical housing 11 is preferably formed with cover flanges 57 affording seats for receiving the peripheral edges of preferably disc-like cover plates 59, 60, which are sealingly secured upon

the open ends of the housing, as by means of fastening screws 61.

Near one end of the housing 11 the same is provided internally with a bracket support lug 63 on which a bracket 65 is fastened, as by means of a clamping screw 67. The bracket 65 is provided with an ear 69 having a circular opening 71. Within the opening the ear is formed to provide an annular seat 73 adapted to snugly receive the rim 77 of a resilient mounting member. This mounting member comprises a disc or diaphragm 79 of resilient, preferably rubber-like material such as neoprene, a synthetic rubber compound. The disc 79 is snugly fitted within and secured to the rim member 77, which preferably comprises a metal ring within and to which the peripheral portions of the diaphragm member 79 are adhered, as by applying heat and pressure. The disc 79 is formed with a central opening within which is mounted a preferably metal sleeve 81 forming a hub in which may be mounted a stem 83, preferably in the form of a threaded screw. This screw serves to secure a bracket 85 on the hub 81. The bracket 85 preferably comprises molded insulating material, such as Bakelite, and has a portion extending at the longitudinal axis of the casing 11 near an end thereof, said bracket portion being formed with an opening for receiving the projecting end of the anode stem 21.

The bracket 65 may conveniently comprise a machine finished die casting of aluminum or other suitable material, and the peripheral edge of the resilient mounting member 79 may be secured in the seat 73 by means of a removable retaining ring 87. The bracket 65, with attached mounting 79 and the insulating bracket 85, may be assembled in the casing 11 through the open end thereof, and the bracket 85 may also form a mounting for aiding in the support of the motive means 27. The support bracket means 63, 85 and the motive means 27 having been assembled in the casing through one end thereof, the generator 13 may then be mounted by inserting the same through the opposite open end of the casing, the anode carrying end being advanced in the casing through the motive means 27 until the stem 21 is received in the opening formed therefor in the bracket 85. The stem 21 may be secured on the bracket by means of a fastening screw 89. The bracket 85 carries a terminal thereon connected with a conductor 91, said terminal being adapted to make electrical contact with the stem 21 when the same is in mounted position on the bracket 85. The conductor 91 is connected with one of the terminals 51 of the cable receptacle whereby the anode of the generator 13, when the same is mounted on the bracket 85, may be electrically connected with one of the conductors of one of the cables 49. Conductors 93 for energizing the motive means 27 may be connected with others of the terminals 51 whereby to energize the motor through said cable 49.

After the generator has thus been secured on the bracket 85, its cathode end may be anchored in position and electrically connected with the cable 50 by means of a bracket 95, preferably comprising a strip of metal anchored on a grounded bracket 97 which in turn is fastened on the inner, or closed, end of the receptacle 53 in the chamber 44. The strip 95 extends to the central axis of the casing 11 and is formed with an opening 99 which receives the projecting end 75 of the cathode stem 29, the member 95 being

attached on the bracket 97 by means of a holding screw 101 after the generator has been introduced and positioned in the casing 11. The member 95 carries a disc 103, of resilient material, secured at its peripheral edges in the opening 99 by means of retaining rings 105 secured to the opposite sides of the member at the opening 99. The disc 103 preferably comprises rubber-like material, such as neoprene, a synthetic rubber, and is formed with a central opening 107 snugly receiving the stem 29 whereby the same is resiliently supported on the member 95. The filament conductors 25 may then be electrically connected with the conductors of the cable 50 by connection at the terminal plate 31 with conductors 109 extending to and electrically connected with the terminals 52. The cathode stem 29 may be grounded by means of a conductor 111 secured to the end of the stem 29 and electrically connected with the grounded mounting member 95.

The casing 11 may be formed in any preferred fashion and may comprise an integral casting. Preferably, however, and as illustrated, the casing 11 comprises a sheet metal tube formed integrally with the chambers 43, 44, the hood 35 preferably comprising a separately formed member welded or otherwise secured to the casing 11 at the opening 33. The flanges 51 at the opposite ends of the casing and the flanges at the open ends of the chambers 43 and 44 may comprise strengthening rings welded or otherwise attached to the casing at the openings thereof.

The cover plates 59 and 60 may be formed in any suitable or convenient fashion and preferably comprise die castings. Each cover member is formed with a central embossment 113 defining an opening therethrough, which opening is normally closed by preferably threaded means. To this end the opening in the cover 59 may be closed by a threaded plug 115, while the opening in the cover 60 is closed preferably by valve gland means 117, the details of which are illustrated in Figure 5 of the drawing.

The valved gland means 117 preferably comprises a threaded fitting 119 adapted to be fastened in the opening to be closed. The fitting 119 is formed with a longitudinal channel 121 therethrough, which channel forms a valve seat 123 facing inwardly of the fitting. Outwardly of the valve seat the channel 121 is enlarged and internally threaded, as at 125, in order to receive a threaded sealing plug 127. The valve seat 123 is adapted to seat a valve member 129, preferably comprising a steel ball, which is normally urged toward valve seating position by means of a valve spring 131 extending in the channel 121 adjacent the ball. The spring 131 is retained in place preferably by means of a plug 133 threaded into an enlarged portion of the channel 121, said plug 133 having a central perforation 135.

The generator 13 having been assembled in the casing 11 and the casing closed by the covers 59 and 60 and by the assembly of the terminal receptacles 53, 54 in the housings 43 and 44, the housing may be charged with a suitable gaseous insulating medium. For the purposes of the present invention, the gaseous insulating medium comprises a chlorine-fluorine derivative of aliphatic hydrocarbons, more particularly the halogen derivatives of methane or ethane. Specifically the present invention teaches the utilization of dichloro-difluoromethane, CCl_2F_2 , or dichloro-tetrafluoroethane, $\text{C}_2\text{Cl}_2\text{F}_4$, and prefer-

ably the latter, as an insulating medium in the casing 11.

Other media having like vapor pressure characteristics may, of course, be employed. The chosen insulating medium, however, should have an appreciable gaseous phase at the ordinary operating temperature of the device being insulated. The normal operating temperature of X-ray generators is substantially above atmospheric temperature, so that either dichloro-difluoromethane or dichloro-tetrafluoroethane may be employed, since both have vapor pressure characteristics such that they exist substantially in the vapor stage even under appreciable pressure at the normal operating temperature of X-ray generators, the boiling point of dichloro-difluoromethane being minus twenty-eight degrees centigrade, while the boiling point of dichloro-tetrafluoroethane is about four degrees centigrade at atmospheric pressure.

Both of these media, in gaseous condition, have dielectric strength appreciably greater than that of dry air and have insulating characteristics rendering them particularly well suited for insulating X-ray generators in shockproof casings, since neither of them have any material effect upon the rubber-like mountings 79 and 103 and both are non-toxic.

The insulating medium may be charged into the casing 11 through the fitting 119 by removing the plug 127 and attaching a conduit leading to a supply source, which may be a receptacle containing the medium in liquid condition. By heating the liquid to vaporize the same, the same may be charged into the casing through the check valve 129. During the charging operation the valve 115 is opened to allow air to escape from the casing, the valve being closed when the air has been displaced. Satisfactory results are obtained by merely flushing the air from the casing by introducing the gaseous insulating medium through the inlet fitting and allowing it to flush out the air, since the presence of a small amount of air in the casing with the insulating gas does not materially impair the insulating effect.

It is preferable, however, to provide for exhausting the air from the chamber, and this may be accomplished by forming the cover plate 59 with a duct 139 opening into the casing through a valve seat 137, the duct opening outwardly of the plate at a preferably threaded port 141 adapted for connection with an exhaust pump. After air has been exhausted from the casing, the plug may be set upon the seat 137 to seal the duct 139 and the insulating gas allowed to enter through the fitting 119 under control of a valve in the conduit between the supply receptacle and the fitting, such valve being kept closed while the chamber is being exhausted of air.

As an alternative method of charging the casing, the fitting 119 may be kept closed or replaced by a solid plug, and the exhausting and charging of the casing accomplished entirely through the duct 139. This may be accomplished by connecting the supply reservoir in the exhaust line to the duct 139. By closing the connection to the reservoir and opening the connection to the pump, the casing may be exhausted of air through the duct 139. Then by closing the connection to the pump and opening the connection to the reservoir, the exhausted casing may be filled with insulating gas through the duct. When sufficiently charged with gas, the plug 115 may be turned to seal the duct 139 at the valve seat 137. It is desirable to make the casing light in weight

and, consequently, the walls thereof are made as thin as possible, with due consideration for requisite strength. The thickness of the casing walls and consequent strength thereof imposes a limitation on the maximum internal pressure to which the casing may safely be subjected. If the casing be sealed as above described and subjected to high temperatures due to the release therein of heat by the operation of the X-ray generator, the gaseous pressure may increase to dangerously high levels if the casing be of light weight, relatively weak construction. The gas pressure in the casing, however, may be kept at its pressure corresponding with room temperature by connecting it with a chamber or zone, which is thermally isolated from and in open communication with the casing. By holding the temperature of the chamber at room temperature, the gaseous medium will flow into and condense in the chamber on any pressure rise in the casing, thus maintaining the pressure at the room temperature pressure of the medium and insuring against the development of excessive pressures in the casing.

To that end, an auxiliary casing 143, forming a supply reservoir, may be provided and fitted with a delivery pipe 145 having an end projecting from the bottom of the casing 143 in position to be secured in the boss 113 of the cover plate 60, in open communication with the interior of the casing 11. The other end of the pipe 145 extends substantially within the casing 143, thereby forming a liquid trap preventing passage of liquid from the casing 143 to the casing 11 through the pipe 145, no matter how the casings may be tilted. The pipe, however, allows free gas passage between the casings.

The casing is formed with a filter opening 147 in its top wall, preferably opposite the inner end of the pipe 145. This opening allows liquid to be charged into the casing 143. The opening is normally closed by a removable plug 149, in which may be fitted a valve member 151 operable outwardly of the plug to control gas flow through the pipe 145. To this end the valve member 151 has an inner end adapted to cooperate with a valve seat 153, at the inner end of the pipe 145, to control gas flow while the casing 11 is being initially evacuated. The valve member 151, normally will be in open position and will be closed only when it is desired to isolate the casing 143 from the casing 11.

The casing 143 is preferably thermally insulated from the casing 11, as by making the pipe 145 of Bakelite or other non-conducting material. The casing 143 consequently will be at a relatively lower temperature than the casing 11, since all of the heat generated by the operation of the tube 13 is liberated within the casing 11. As a consequence, any condensation of gas, during heating and cooling of the casing 11 within the range of its maximum operating and stand-by temperature, will take place in the relatively cool storage casing 137 and not in the chamber 11. At the same time, the liquid stored in the casing 143 provides a constantly available source of gas which automatically replenishes any gas lost by leakage.

It is thought that the invention and its numerous attendant advantages will be fully understood from the foregoing description, and it is obvious that numerous changes may be made in the form, construction and arrangement of the several parts without departing from the spirit or scope of the invention, or sacrificing any of its attendant advantages, the form herein disclosed being

a preferred embodiment for the purpose of illustrating the invention.

The invention is hereby claimed as follows:

1. X-ray apparatus comprising a sealed casing forming a compartment, an X-ray tube in said compartment, a gaseous insulating medium enveloping the tube in said casing, said medium having vapor pressure characteristics such that it may exist, under pressure, in a liquid phase at normal atmospheric temperature, a storage chamber connected with said compartment and heat insulating means thermally insulating said chamber from said compartment, the walls of said chamber being exposed to the surrounding atmosphere to maintain said chamber at a temperature sufficiently low to maintain an insulating medium, in liquid condition, therein.

2. X-ray apparatus comprising a sealed casing forming a compartment, an X-ray tube in said compartment, a gaseous insulating medium enveloping the tube in said casing, said medium having vapor pressure characteristics such that it may exist, under pressure, in a liquid phase at normal atmospheric temperature, a storage chamber and insulated conduit means connecting said chamber with said compartment to thereby thermally insulate the chamber from the compartment, the walls of the chamber being exposed to surrounding atmosphere to maintain a supply of insulating medium, in liquid condition, in the chamber.

3. X-ray apparatus comprising a sealed casing forming a compartment, an X-ray tube in said compartment, a gaseous insulating medium enveloping the tube in said casing, said medium having vapor pressure characteristics such that it may exist, under pressure, in a liquid phase at normal atmospheric temperature, said casing having a storage chamber connected with said compartment, means for cooling the walls of said storage chamber to allow a supply of the medium in liquid condition to be stored therein whereby an atmosphere of the medium in gaseous condition may be maintained in said compartment, and trap means normally preventing the medium from entering the compartment from the chamber when in liquid condition.

4. X-ray apparatus comprising a sealed casing forming a compartment, an X-ray tube in said compartment, and an insulating medium enveloping the tube in said casing, said tube being supported in the compartment on resilient support means comprising a disk of rubber-like material, a bracket element carried by the casing, and a tube supporting element, one of said elements being secured to the said disk at the edge thereof and the other of said elements engaging the disk inwardly of its edge whereby to resiliently support the tube in the casing.

5. X-ray apparatus comprising a sealed casing forming a compartment, an X-ray tube in said compartment, and a gaseous insulating medium enveloping the tube in said casing, said tube being supported in and electrically insulated from the compartment by resilient support means comprising a disk of rubber-like material substantially inert to said gaseous insulating medium, a bracket element carried by the casing, and a tube supporting element, one of said elements being secured to said disk at the edge thereof and the other of said elements engaging the disk inwardly of its edge whereby to resiliently support the tube in the casing.

6. X-ray apparatus comprising a casing having an open end and forming an elongated cavity for

an X-ray tube, bracket means in said cavity in position to receive and support one end of an X-ray tube when the same is inserted into the cavity from the open end of the casing, said bracket means comprising a disk of rubber-like material substantially inert to said insulating medium, a bracket element carried by the casing and a tube supporting element, one of said elements being secured to said disk at the edge thereof and the other of said elements engaging the disk inwardly of its edge whereby to resiliently support the tube in the casing, and a hanger mountable in said casing after insertion of the tube in the casing and on the bracket, said hanger being mountable in position to receive and support the end of the tube remote from said bracket means.

7. X-ray apparatus comprising a casing having an open end and forming an elongated cavity for an X-ray tube, bracket means in said cavity in position to receive and support one end of an X-ray tube when the same is inserted into the cavity from the open end of the casing, a hanger mountable in said casing after insertion of the tube in the casing and on the bracket, said hanger being mountable in position to receive and support the end of the tube remote from said bracket means, and a demountable cover for sealing the open end of the casing, said hanger and bracket comprising resilient rubber-like suspension elements having shock absorbing characteristics whereby to support the tube in vibration free fashion in the casing.

8. X-ray apparatus comprising a casing having an open end and forming an elongated cavity for receiving an X-ray tube, means for supporting the tube in the cavity and for electrically connecting the tube with electrical operating circuits disposed outwardly of the casing, a removable cover in spaced relation with said supporting means for sealing the open end of said casing, and inlet means on said cover for delivering a gaseous insulating medium into the cavity from a source outside of said casing.

9. X-ray apparatus comprising a casing having an open end and forming an elongated cavity for receiving an X-ray tube, means for supporting the tube in the cavity and for electrically connecting the tube with electrical operating circuits disposed outwardly of the casing, a removable cover for sealing the open end of said casing, and inlet means on said cover for delivering a gaseous insulating medium into the cavity from a source outside of said casing, said inlet means comprising means on the cover forming a duct therethrough, the duct being formed with a valve seat facing into the cavity, a spring pressed valve on the seat and a seal plug removably secured in the duct outwardly of the valve seat.

10. X-ray apparatus comprising a casing having an open end and forming an elongated cavity for receiving an X-ray tube, means for supporting the tube in the cavity and for electrically connecting the tube with electrical operating circuits disposed outwardly of the casing, a removable cover for sealing the open end of said casing, said cover being formed with a duct therethrough communicating with said cavity, the duct being formed with a valve seat facing into

the cavity, and a spring pressed valve on the seat past which a gaseous insulating medium may be delivered through said duct and into the cavity from a source outside of said casing.

- 5 11. X-ray apparatus comprising a casing having an open end and forming an elongated cavity for receiving an X-ray tube, means for supporting the tube in the cavity and for electrically connecting the tube with electrical operating circuits disposed outwardly of the casing, a removable cover for sealing the open end of said casing, said cover being formed with a duct therethrough communicating with said cavity, the duct being formed with a valve seat facing into the cavity, a spring pressed valve on the seat past which a gaseous insulating medium may be delivered through said duct and into the cavity from a source outside of said casing, and a valved vent in said casing remote from the open end thereof to allow displacement of air from the cavity in filling the same with said insulating medium through said duct.

- 20 12. X-ray apparatus comprising a casing having an open end and forming an elongated cavity for receiving an X-ray tube, means for supporting the tube in the cavity and for electrically connecting the tube with electrical operating circuits disposed outwardly of the casing, a removable cover for sealing the open end of said casing, and inlet means on said cover for delivering a gaseous insulating medium into the cavity from a source outside of said casing, said inlet means comprising a storage chamber for the insulating material in liquid condition, the storage chamber being in open communication with said cavity through a duct extending in said cover and a liquid trap normally preventing entrance of liquid through said duct from the chamber to the cavity.

- 30 13. X-ray apparatus comprising a casing having an open end and forming an elongated cavity for receiving an X-ray tube, means for supporting the tube in the cavity and for electrically connecting the tube with electrical operating circuits disposed outwardly of the casing, inlet means on said casing for delivering a gaseous insulating medium into the cavity from a source outside of said casing, and a valved vent in said casing remote from said inlet means to allow displacement of air from the cavity in filling the same with gas through said inlet.

- 40 14. X-ray apparatus comprising a casing having an open end and forming an elongated cavity for receiving an X-ray tube, means for supporting the tube in the cavity and for electrically connecting the tube with electrical operating circuits disposed outwardly of the casing, inlet means on said casing for delivering a gaseous insulating medium into the cavity from a source outside of said casing, and a valved vent in said casing remote from said inlet means to allow displacement of air from the cavity in filling the same with gas through said inlet, said valved vent comprising means forming a venting channel in the walls of the casing and a valve member operable outwardly of the casing for sealing said channel.
